UNITED STATES PATENT OFFICE.

CHARLES E. CHAPMAN, OF CHICAGO, ILLINOIS.

JEWELRY TRAY.

1,425,317.

Specification of Letters Patent. Patented Aug. 8, 1922.

Application filed August 26, 1921. Serial No. 495,578.

To all whom it may concern:

Be it known that I, CHARLES E. CHAPMAN, a citizen of the United States, residing at Chicago, in the county of Cook and State of Illinois, have invented a certain new and useful Improvement in Jewelry Trays, of which the following is a full, clear, concise, and exact description, reference being had to the accompanying drawings, forming a part of this specification.

My invention relates to automatically locking jewelry trays, and more particularly to that type of tray wherein jewelry is adapted to be carried, either upon cards or loosely; being an improvement over my pending application Serial No. 400,165, filed July 30, 1920.

While my invention relates to trays for carrying jewelry and the like, I do not intend to limit myself to such use solely, as it is apparent that by slight variations in structure, the tray may be used for displaying objects of similar or even of dissimilar character.

In my prior application, I have fully set out the utility of this type of tray and particularly the marked advantage it secures over the prior art method of handling jewelry. The trays provided heretofore carry the jewelry so that it protrudes from the top edge thereof, with no means provided for lowering the articles of display within the tray when it is desired to remove the jewelry to the vault at night—this being customary in the practice of the jeweler. Consequently, the jewelry has to be removed, piece by piece, from the tray and placed in the vault at night, the task of replacing the same in the morning being thereby caused.

The preferred manner of caring for jewelry at night is to remove the trays from the showcases and windows, and to stack them in the vault. But, as vaults have a limited capacity, a practical difficulty of stacking away all the trays, without waste of space caused by protruding articles in the trays, presented itself.

The object of the present invention is the provision of an improved form of tray, which overcomes this difficulty, and which allows the removal and replacement of the jewelry at night and in the morning, respectively, in the shortest time possible. Adjustable shelves are provided on which the jewelry is hung, and are adapted to have a pivotal movement to permit various posi-

tions in order to not only bring the jewelry entirely within the tray, but to obtain the proper angle thereof to secure the proper light reflection, which is considered of high importance in the art of jewelry display.

This invention is particularly directed to an improved form of latch mechanism for locking the shelves in the various positions. The present form of latch mechanism insures a positive action and easy operation, and is disposed so as to be conveniently accessible. Other advantages of my invention as hereinbefore set forth will appear from the following detailed description and claims taken with an inspection of the accompanying drawings wherein I have illustrated the preferred embodiment of my invention. The particular tray shown is merely illustrative and the details thereof may be varied.

In the drawings:

Figure 1 is a top plan view of a jewelry tray embodying my invention;

Figure 2 is a detailed fragmentary view, illustrating the latch mechanism at a larger scale; and

Figure 3 is a top plan view of Figure 2, with a partial showing of a shelf included.

Referring to Figure 1, the tray 1 comprises the side walls 2 having the ledges 3. The ledges 3 are preferably disposed along the lower end of the walls 2, and provide an open bottom for the tray, the purpose of which will hereinafter be mentioned. Either before or after the assembly of the tray, holes 4 are bored in the opposite faces of one pair of sides. The holes 4 are in parallel alignment.

In assembling the tray, bearings 5 are tightly inserted in the holes 4, so that the inner ends of the bearings 5, which face each other oppositely, may receive the ends of the rods 6, in journaled relation. The rods 6 carry shelves 7, which may be of any kind of material desired, although sheet metal better serves the purpose. The form of shelf shown herein is merely illustrative, showing one of the many ways of suitably retaining a card 8, to which is fastened some article of sale, such as jewelry. The shelf may be made out of one piece of metal, the stamping of which might be performed in one operation. The lower portion 9 during the stamping operation, or thereafter, is provided with the spring retaining fingers 10, which serve to bear against the card 8 to hold the

same in proper position while in the tray. These fingers are so formed that they resiliently bear against the back 11 of the shelf 7. Any number of fingers 10 may be provided for a single card, although I have shown one finger against the card, permitting a wedged engagement of the latter between the finger 10 and back portion 11. That portion between the respective fingers 10 is preferably retained, as shown at 12, in order to present a finished effect. The whole shelf 7, or any part thereof, may be covered with fabricated material as desired. It is to be here noted that the entire lower portion of the shelf 7 may be formed in one piece, if so desired. At the end of the shelf 7, a lug 13 is provided, which is at right angles to the back 11. To the lug 13 is riveted the tension member 14 by means of rivets 22.

The tension member 14 serves as a common connecting member for all the shelves 7, and also serves to control their various positions, so that when the member 14 is locked at a certain adjustment along the side of the tray, the shelves 7 will have a certain angular adjustment, being relative to the tray frame. It will be noted that the pivot rods 6 have been provided parallel 30 to each other, and therefore, the shelves 7 will be parallel, each moving in a plane parallel to the others. This arrangement is only preferable, but may be varied, if so desired. The common connecting member 35 14 preferably never moves out of the side plane of the tray, which is advantageous in that it eliminates all possibility of interfering with stacking and causing the tray to appear unornamental.

40 One end of the common connecting member 14 is enlarged, as indicated at 15, with the lower edge toothed. Directly below this is disposed a tripping member 16 which is pivotally mounted to the inner side of the ledge 3, by means of the screw 17'. The ledge 3, at this point, is grooved away to permit the upper edge of the tripping member 16 to lie flush with the ledge 3, when the former is disengaged from the toothed 45 portion 15 of the member 14. At one end of the tripping member 16, a lug 17 extends laterally toward the tray, which lug engages with the teeth of the member 14. It is to be noted that I have provided means for holding 50 the tripping member 16 slightly raised in this direction, in order that the member 16 will be held in positive engagement with the teeth. This means comprises a wire spring 18 anchored in the ledge 3, having 55 its free end tensionally engaging the under side of the lateral lug 19 of the tripping member 16. The lug 19 is formed preferably in front of the pivot point, so that the spring 18 may act upon the member 16 to 60 obtain the desired tilting. The opposite

end of the tripping member is formed with a finger lug 20, which turns laterally outward to be in a position for convenient engagement by a finger of the operator. An important feature is that no portion of the 70 tripping member 16 will project out of the tray at the bottom side. When the shelves 7 are adjusted in vertical position, the tripping member will assume a position where the thumb member 20 will be just within 75 the lower area of the tray. The magnitude of swing of the shelves 7 about their pivots may be controlled by the toothed portion 15 being either moved forward or backward of the lug 19.

80 The tray frame is constructed so as to provide an open bottom in order to allow light to pass therethrough to add to the volume of light thrown upon the jewelry being displayed; and, if the light passes from the front to the rear, then to allow light to pass therethrough to the lower portions of the show case or window to illuminate properly the articles there on display.

85 Without further elaboration, the foregoing 90 will so fully explain the gist of my invention, that others may, by applying current knowledge, readily adapt the same for use under varying conditions. The tripping member 16 may be arranged differently, 95 engaging the common connecting member 14 in a manner other than that shown. The shelves 7 and their pivotal connections with the member 14 may be varied, and so may the particular design of the shelf itself. 100 Such details and many others may obviously be changed without eliminating certain features which may properly be said to constitute the essential items of novelty involved in my invention, which items are intended 105 to be defined and secured by the following claims.

I claim:

1. In combination, a tray comprising a frame, shelves pivoted therein, a common 110 connecting element pivotally connecting said shelves, a locking member pivotally disposed within said frame, and means on the under side of said common connecting element and on one of the ends of said pivotal locking 115 member which engage each other for effecting positive locking relation between said common connecting element and said locking member.

2. In combination, a tray comprising a 120 frame, shelves pivoted therein, a common connecting element pivotally connecting said shelves, a portion of the under side of said common connecting element being provided with teeth, a pivotally mounted locking 125 member disposed on said tray and adjacent to said toothed portion, and means for holding said locking member in engagement with said toothed portion.

3. In combination, a tray comprising a 130

- frame, shelves pivoted therein, a common connecting element pivotally connecting said shelves, a portion of the under side of said common connecting element being provided 5 with an engaging surface, a locking member pivotally mounted within the tray and adjacent to said engaging surface, a spring connected to the tray, said spring engaging said locking member for normally holding 10 it in engagement with said surface.
4. In combination, a tray comprising a frame, shelves substantially of greater height than the frame pivoted therein, a common connecting element for said shelves lying 15 parallel to the side of the tray, a latch member for engaging one end of said common connecting member whereby the shelves may be held in any angular position, and a por-
- tion on said latch member formed so that it may be engaged by the finger through the 20 under side of said frame.
5. In combination a tray comprising a frame, shelf members pivoted in said frame, a common connecting link for all of said pivotal members, and pawl and ratchet means 25 connecting the link and the frame to permit the shelves to be raised to any desired position and held there, the pawl being manually releasable to permit the shelves to be lowered, said pawl and ratchet means being 30 disposed within the frame when the shelves are lowered.

In witness whereof, I hereunto subscribe my name this 24th day of August, 1921.

CHARLES E. CHAPMAN.
